METALLURGICAL FURNACE

Charles R. Kuzell, Clarkdale, Ariz., assignor, by
mesne assignments, to Phelps Dodge Corpora-
tion, New York, N. Y., a corporation of New
York

Application January 5, 1933, Serial No. 650,236

9 Claims. (Cl. 263—46)

This invention relates to metallurgy and has for an object the provision of improved metallurgical apparatus. More particularly, the invention contemplates the provision of an improved reverberatory furnace structure.

The present application is a continuation in part of my application Serial No. 490,884, filed October 24, 1930 (United States Patent No. 1,896,178, issued February 7, 1933).

10 Reverberatory furnaces are usually mounted on foundations embedded in the ground. The upper surfaces of the foundations are usually disposed at or slightly below the surface of the ground which forms the operating floor or on which the operating floor is supported. The furnace chambers, including the floors or bottoms, usually extend substantially entirely above the ground.

15 The furnaces are usually provided with vertical beams for supporting the side walls. Each side of the furnace is provided with a plurality of similarly spaced beams. The beams extend from points slightly below the ground line to points above the upper surface of the roof. The beams 20 are wedged between the furnace walls and a concrete toe at the bottom and tie rods extending transversely over the top of the furnace roof connect the beams at the top. Structures of this type are semi-rigid and do not normally allow 25 expansion and contraction at the operating floor line due to changes of temperature and pressure within the furnace.

20 During the course of normal furnace operations, considerable outward pressure is continuously exerted against the lower portions of the beams, and it frequently happens that the concrete toe, or the wedging means between the toe and beam, crumbles and permits the lower portion of one or more of the beams to move outwardly. Movement of the beams results in the 25 withdrawal of the support necessary for maintaining the wall in its proper shape and condition with the result that the wall is weakened and bulges outwardly. Continued operation of 30 a furnace in such condition is very dangerous in view of the possibility of the weakened wall crumbling and permitting the molten material to flow onto the operating floor.

35 Also, during the course of normal furnace operations, changes of temperature within the foundations or furnace hearth or accretions thereon cause outward expansion against the foundation walls which is transmitted through the ground to external structures, such, for example, as piers under building columns and the foundations of

adjacent furnaces, with consequent danger to the stability of such external structures.

The present invention contemplates the provision of a reverberatory furnace structure comprising a foundation which is so spaced from the ground in which external structures may be embedded that movement due to expansion within the foundations will not be transmitted to such external structures. In the preferred arrangement, the portions of the walls of the furnace 10 foundation which might be affected by expansion within the foundation hearth, etc. extend into space from their supporting structure, and they are free from contact, direct or indirect, with external formations or structures. 15

The invention further contemplates the provision of improved supporting means for furnace walls. The wall supporting means preferably include resilient supporting members which offer yielding resistance to the movement of upright 20 braces or beams which bind the side walls of the furnace.

A preferred arrangement of apparatus includes a reverberatory furnace provided with firing means adjacent two opposite ends and having a 25 gas discharge opening in the roof substantially centrally between the firing ends. A boiler plant is disposed directly above the roof of the furnace adjacent the gas discharge opening, and the heating chamber of the boiler plant communicates with the interior of the furnace through a vertical flue surrounding the gas discharge opening. 30

The invention will be better understood from a consideration of the following description in 35 conjunction with the accompanying drawings, in which:

Fig. 1 is a longitudinal elevation, partly in section, of a reverberatory furnace and superimposed boiler plant; 40

Fig. 2 is a section taken substantially along line 2—2 of Fig. 1; and

Fig. 3 illustrates a method of tying-in the lower end portions of side wall supports.

The reverberatory furnace 10 is provided with 45 firing means in the form of burners 11 for introducing mixtures of air and powdered coal into the interior of the furnace chamber at its two opposite ends. A gas discharge opening 12 is provided in the furnace roof 13 midway between the 50 firing ends.

The furnace walls are supported on a foundation consisting of reinforced concrete walls 14 provided with ledges for supporting vertical beams or buck stays 15 which engage the side 55

walls of the furnace. Short horizontal I-beams 16 having their ends loosely supported by brackets on the concrete foundation walls 14 and in recesses in the parallel concrete walls or piers 17 provide supporting means for intermediate working platforms 18, from which repairs or other operations may be conducted. Movement of the foundation wall is not transmitted to the piers 17 through the beams 16. Each side wall of the furnace is provided with a plurality of similarly spaced vertical supporting beams 15, and the upper ends of opposite beams are connected by tie rods 20 having threaded ends provided with suitable nuts to permit adjustment to compensate for expansion of the furnace area.

The lower end portions of the vertical beams are held in position against the furnace walls by means of the rods 21 each having one end anchored against a foundation wall 14 and the other end extending to a point beyond the vertical supporting beams on the opposite side of the furnace. The rods 21 are encased in pipes 22 which extend through the foundation walls and the earth between the walls and which are of greater inside diameter than the diameter of the rods. The ends of the rods 21 project into open spaces between the walls 14 and 17. The ends of the rods 21 are threaded and provided with nuts 23. A washer 24 is mounted on the lower end portion of each rod between the nut and the outer faces of a pair of spaced I-beams 25 the inner faces of which bear against a beveled surface on the foundation wall. A helical spring 26 is mounted axially on the upper end portion of each rod 21 between a washer 27 which bears against the nut and a plate 30 which bears against the outer faces of two parallel I-beams 31. The inner faces of the I-beams 31 lie in contact with a beveled bearing plate 32 which extends between and bears upon the outer faces of two adjacent vertical beams 15.

The tie rods 21 are disposed at such an angle and sufficient distances below the furnace bottom that they are not adversely affected by high temperatures within the foundation. The piers 17 and the tie rods 21 are so formed and so arranged relatively to one another that the tie rods may be withdrawn readily for repair and replacement.

The furnace chamber is provided with slots 33 in its roof and side walls on opposite sides of the gas discharge opening to permit the insertion of a damper or curtain 34 for closing off one end portion of the furnace to permit independent operation of the other end portion. The slots 33 may be wide expansion joints which are normally closed by suitable bricks or tiles 35. The dampers or curtains may be of any suitable construction, and they may be mounted for use in any suitable manner. A sheet metal casing provided with suitable connections for permitting circulation of water therethrough forms a suitable damper or curtain. The dampers may be suspended above the furnace by means of pulleys and cables (not shown). The slots and dampers may be of any suitable configuration.

Three tap hole blocks 36 provided with tap holes for withdrawing matte are provided in one side wall of the furnace. One tap hole block is located at about the longitudinal center of the side wall and one on the opposite side of each damper slot. A skimming block 37 and opening are located at about the longitudinal center of the opposite side wall.

A boiler plant consisting of two heating chambers 40 each having a standard make of boiler 41 mounted therein is mounted directly above the furnace on a frame structure 42 which straddles the furnace. The upright members of the frame structure 42 are supported by the concrete piers 17. The heating chambers 40 are connected to the reverberatory furnace by means of a short vertical flue 43 which surrounds the gas discharge opening 12 in the roof of the furnace. Water cooled dampers 44 are provided for closing the heating chambers when necessary.

The reverberatory furnace illustrated in the drawings is, in effect, a double reverberatory and it may have a length equal to substantially twice the length of the normal furnace. The apparatus of the invention may include a reverberatory furnace having firing means at one end only instead of a furnace having firing means at two opposite ends.

I claim:

1. The combination with a reverberatory furnace of a supporting frame comprising a set of upright supports disposed on opposite sides of the furnace in contact with the side walls and supported upon a foundation, means for adjustably connecting the upper portions of said supports, and means for individually connecting the lower end portions of said upright supports to the foundation.

2. The combination with a reverberatory furnace of a supporting frame comprising a set of upright supports disposed on opposite sides of the furnace in contact with the side walls and supported upon a foundation, means for adjustably connecting the upper portions of said supports, and means for individually connecting the lower end portions of said upright supports yieldingingly to the foundation.

3. Apparatus of the class described comprising a furnace chamber, a foundation for the furnace chamber, an upright side wall supporting member, a tie rod anchored in the foundation and extending to a point adjacent the upright supporting member, and a helical spring mounted on said tie rod and operatively associated with said upright support to afford yielding resistance to its movement.

4. Apparatus of the class described comprising a reverberatory furnace chamber, a foundation for supporting the furnace chamber, an upright side wall support having its lower end disposed adjacent the upper end of the foundation wall, an inclined tie rod anchored in the foundation adjacent the bottom thereof and extending to a point adjacent the upright support, and spring means mounted on said tie rod and operatively associated with said upright support to afford yielding resistance to its movement.

5. Apparatus of the class described comprising a reverberatory furnace chamber, a foundation for supporting the furnace chamber, an upright supporting member disposed in contact with one side wall of the furnace chamber and extending to a point adjacent the upper end of the adjacent foundation wall, and a tie rod having one end portion operatively associated with the lower end portion of the upright support and having its other end portion anchored against the opposite foundation wall.

6. Apparatus of the class described comprising a reverberatory furnace chamber, a foundation for supporting the furnace chamber, an upright supporting member disposed in contact with one

side wall of the furnace chamber and extending to a point adjacent the upper end of the adjacent foundation wall, an inclined tie rod extending through the foundation with its upper end disposed adjacent the lower end of the upright support and its lower end projecting beyond the opposite foundation wall, means for anchoring the lower end portion of the tie rod against the foundation wall, and spring means mounted on the upper end portion of the tie rod and operatively associated with the upright support to afford yielding resistance to its movement.

7. The combination with a reverberatory furnace of a vertical beam engaging a side wall and supported upon a foundation, adjustable means for limiting the movement of the upper end portion of the beam, and resilient means for individually fastening the lower end portion of the beam to the foundation.

8. A metallurgical furnace comprising side walls resting upon a foundation wall and held in

position by means of upright supports the lower end portions of which are adjacent to the foundation wall, and a tie rod for individually anchoring the lower end portion of each upright support to the adjacent foundation wall, one end of said tie rod being associated with the lower end portion of the upright support and the other end being anchored to the opposite foundation wall.

9. In a metallurgical furnace comprising side walls resting upon a foundation wall and held in position by means of upright supports the lower end portions of which are adjacent to the foundation wall, and a tie rod for individually anchoring the lower end portion of each upright support to the adjacent foundation wall, one end of said tie rod being yieldingly associated with the lower end portion of the upright support and the other end being anchored to the opposite foundation wall.

CHARLES R. KUZELL.
